METHOD OF AND APPARATUS FOR
CRUSHING ROCK

Drayton A. Silver, Goldendale, Wash.

Application June 5, 1933, Serial No. 674,382

7 Claims. (Cl. 83—46)

This invention relates generally to the art of comminuting materials, and particularly to a rock crusher.

The main object of this invention is the evolution of a method of grinding materials.

The second object is to provide a rock crusher which will thoroughly crush a given quantity of rock in a minimum amount of time with the expenditure of a minimum amount of power without being destructive to the apparatus itself.

The third object is to crush rock in a natural manner—that is by using the larger pieces of rock to crush the smaller pieces instead of obtaining the crushing action at the expense of a wearing action which is present in a large degree in existing devices.

These, and other objects, will become more apparent from the specification following as illustrated in the accompanying drawing, in which:

20 Fig. 1 is a perspective view of the device with parts broken away in section.

Fig. 2 is a section taken along the line 2—2 in Fig. 1.

Fig. 3 is a somewhat diagrammatic section taken along the line 3—3 in Fig. 1.

Fig. 4 is a section taken along the line 4—4 in Fig. 1.

Fig. 5 is a section taken along the line 5—5 in Fig. 1.

Fig. 6 is a section taken along the line 6—6 in Fig. 1.

Similar numbers of reference refer to similar parts throughout the several views.

Referring in detail to the drawing, the device consists of a conveyor 10 provided with heavy flights 11, and preferably driven from its upper end by a gear 12 through a shaft 13 while its lower end passes around the idler sprockets 14 on the shaft 15. The sides of the conveyor 10 are closed by the sides 16 and 17. The lowermost portion of the sides 16 and 17 is joined by a curved bottom 18 around which the flights 11 swing as they pass around the idler sprockets 14.

45 Between the sides 16 and 17 and connecting with the curved bottom 18 is a sloping plate 19 upon which is placed an anvil composed of a plurality of spaced bars 20 whose interstices become filled with particles 21 of crush rock.

50 The conveyor 10 is steeply inclined, being almost vertical, and having under its discharge side at the upper end thereof, an inclined chute 22 which carries the pieces of rock 23 laterally and discharges them into the sloping screen 24 provided with perforations 25.

The materials which do not pass through the screen 24 are returned by means of a deflecting plate 26 through an opening 27 in the side 16 from whence they will fall upon a deflector plate 28 and be directed against the upwardly traveling rocks 23 on the flights 11, finally striking the anvil bars 20 with great force, being further reduced in size as the result thereof, after which they again start on the upward journey on the conveyor 10.

5 Those particles which pass through the perforations 25 in the screen 24 are collected in the chute 29 and carried by a duct 29—A into the concentric screens 30, 31 and 32 which are supported by the spider 33 on the shaft 34, to which motion is imparted by the chain 35 which passes around the sprocket 36.

10 The materials 37 are delivered to the interior of the revolving screen 30, together with water 20 which is admitted through a pipe 38 under the control of a valve 39. The particles 40 which pass through the screen 30 are subjected to a screening action on the screen 31, and the particles 41 are now passed over the screen 32 the resulting fine materials 42 being carried away 25 through a collector trough 43 to a comminuting machine or storage bin (not shown). Those materials 37, 40 and 41 which pass over the ends 30 of their respective screens 30, 31 and 32 enter the funnel 44 and pass through the upright pipe 45 to the upper end of the anvil bars 20.

15 The purpose for separating the bars 20 is to make the top surface of the anvil self-sharpening thereby greatly improving the crushing and 35 grinding action.

20 It can be seen from the foregoing that rocks passing through this machine will be subjected to a violent crushing by contact with other rocks, and also by contact with the heavy conveyor 40 flights 11 and the anvil bars 20 under the force of gravity, and that all of the action employed in existing forms of crushers which is so destructive to the mechanism itself is entirely eliminated.

25 It can also be seen that the materials will pass 45 through the machine as often as required to reduce them to a given degree of fineness without attempting to obtain the full reduction simultaneously, thereby greatly reducing the wear and tear on the parts, the power consumed and at 50 the same time maintaining the maximum capacity for the machine.

Furthermore, water is introduced only at the latter portion of the operation and in a relatively small quantity, the purpose being to minimize 55

the amount of loss due to the fine gold being held in suspension in the muddy water. In other words, in ordinary crushing machines in order that all of the material may be ground to a desired fineness a large portion of it is ground too fine, and these fine particles of rock and precious metals are held in suspension making it extremely difficult to recover the metals from the solution.

10 I am aware that many methods have been employed in the comminuting of materials and that many forms of apparatus have been employed in the practice of these methods, it is therefore not my intention to cover all forms and modifications 15 of such but I do intend to cover all such modifications as fall fairly within the appended claims.

I claim:

1. A method of grinding materials consisting of 20 progressively elevating a mixture of coarse and fine materials in stream formation, then segregating the coarsest of said materials and discharging same against said ascending stream for the purpose of further reducing the size of the pieces in the upwardly moving stream and in the downwardly moving stream and returning all of said reduced portions to said upwardly moving stream.

2. A rock crusher having in combination a rock elevating conveyor having a segregating screen at the upper discharge end thereof, a chute by 30 means of which the coarser pieces of rock from said screen will be projected against the upwardly moving side of said conveyor, a revolving screen having an inlet chute for taking the finer materials passing through said segregating screen, a second chute adapted to withdraw the finest portions from said revolving screen and a third chute for returning the coarser portion from said revolving screen to said conveyor.

3. A rock crusher having in combination a rock 40 elevating conveyor, means for segregating the large pieces of rock at the top of said conveyor and discharging same against the upwardly moving side of said conveyor, an anvil at the lower end of said conveyor against which descending pieces of rock may strike and be directed into the 45 intake of said conveyor, and means for removing

the fines from said machine as rapidly as they are produced comprising a system of screens whereby the partially crushed materials are segregated and the coarser portions thereof returned to the intake of said conveyor.

4. A crusher as described in claim 2 including an anvil at the bottom of said elevator against which the coarser pieces of rock being returned to said crusher are directed.

5. A rock crusher having in combination an 10 inclined elevating conveyor having a screen at the upper end thereof including a conduit for projecting the coarsest material which passes over said screen against the upwardly moving conveyor flights, a second chute for receiving the 15 materials which pass through said screen, a revolving screen fed by said second chute, a chute for collecting the fines from said revolving screen and a third chute taking the coarser material from said revolving screen and returning same to 20 said conveyor.

6. The crusher described in claim 5, together with an anvil disposed at the lower end of said conveyor against which the intermediate grades of material may be projected and means for introducing water to said crusher by way of the revolving screen.

7. A rock crusher having in combination an inclined conveyor, a collector disposed at the bottom of the conveyor constituting a loading point 30 thereof, the upper end of said conveyor constituting its discharge end, an inclined anvil at the loading point of said conveyor from which materials can pass into said collector, said anvil being at the lower end of the upwardly traveling run 35 of the conveyor, said anvil comprising a plurality of spaced bars along whose uppermost edges materials may pass into the collector where they will be packed up by said conveyor, a plurality of screens having means for projecting its coarsest 40 materials against the upwardly moving portion of the conveyor, another of said screens serving to withdraw the fines from the crusher and to return the coarser portions to the conveyor.
